UNITED STATES PATENT OFFICE

154,249

DESIGN FOR A PROJECTION LANTERN

Charles F. Dutton, Rocky River, Ohio

Application February 4, 1948, Serial No. 144,269

Term of patent 14 years

(Cl. D61—1)

To all whom it may concern:

Be it known that I, Charles F. Dutton, citizen of the United States of America, residing at Rocky River, county of Cuyahoga, State of Ohio, U. S. A., have invented a new, original, and ornamental Design for a Projection Lantern, of which the following is a specification, reference being had to the accompanying drawings, forming a part thereof:

In the drawings, Fig. 1 is a perspective view of the projection lantern looking toward the front left corner and showing my new design; Fig. 2 is a front elevation of the projection lantern; and Fig. 3 is a rear elevation of the projection lantern.

I claim:

The ornamental design for a projection lantern, as shown and described.

CHARLES F. DUTTON.
